BEAM TUBE SWITCHING CIRCUITS

John R. Bathke, Paoli, Pa., assignor to Burroughs Corporation, Detroit, Mich., a corporation of Michigan

Application August 22, 1955, Serial No. 529,661

6 Claims. (Cl. 315--21)

This invention relates generally to multi-position electron beam position tubes and more particularly to means and methods for clearing and resetting the beam to a "0" position in a multi-position electron beam position tube circuit.

In recent years there has been developed a tube having a plurality of compartments each containing one of a plurality of target electrodes arranged concentrically around an elongated cathode. Each of the target electrodes is associated with a corresponding spade electrode used for locking the cathode ray beam in position upon its target electrode in a selected compartment. A magnetic field is created substantially parallel to the elongated cathode throughout the tube so that an electron beam formed at the cathode of the tube will tend to follow a substantially equipotential path. For this reason the tubes are known as magnetron beam switching tubes. Means are provided including the spade electrodes to create an electrostatic field to establish a substantially equipotential line from a particular target electrode to the cathode so that the electron beam will flow from the cathode to a single compartment defined by the said particular target. A small portion of the electron beam locks upon the associated spade electrode and reduces its potential by means of a load impedance to thereby direct the remainder of the electron beam upon the corresponding target electrode.

Because of the magnetic field, the electron beam has a tendency to continuously rotate in a tight spiral around the cathode in one direction and would re-enter the cathode if it were not locked upon a particular spade electrode. When a substantially equipotential line is created between the cathode and one of the targets a beam is formed. If the beam is formed in one compartment and the equipotential line is directed to that compartment adjacent to the compartment upon which the electron beam is impinging, the electron beam is caused to advance to the said adjacent compartment where it locks upon the spade electrode thereof. In some of the earlier tubes of this type, the locking action may be accomplished by lowering the potential of either the spade electrode or the target electrode. This type of tube is described in the U. S. Patent 2,591,997 issued to N. E. G. Backmark. A more recent development has resulted in the provision of a switching or control grid electrode in each compartment. Such tubes are described in the U. S. Patent 2,721,955, of Sin-pih Fan and Saul Kuchinsky, issued October 25, 1955. The switching electrode of one compartment is maintained at a positive potential, and upon being reduced sufficiently in potential, performs the function of establishing an equipotential path between the cathode and a spade electrode of an adjacent compartment to cause the electron beam to switch across the spade electrode and become locked in the adjacent compartment. If the potentials of successive ones of said switching electrodes are caused to assume a potential such as to establish an equipotential path between the associated compartment and the cathode, the

electron beam will be caused to step consecutively from one compartment to the next. This has been accomplished in one manner by connecting one set of alternate switching electrodes (hereinafter referred to as even numbered electrodes) to one output terminal of a circuit such as a flip-flop or binary circuit and connecting the other set of (odd numbered) alternate switching electrodes to the other output of the flip-flop or binary circuit. Successive output pulses from the flip-flop circuit would then cause the electron beam to advance progressively from one compartment to the next.

It has also been known in the prior art that the beam may be switched from one target to another by means of lowering the potential of the individual spade electrodes.

15 This type of switching is described in the above mentioned Backmark patent. Although highly successful for use in systems which progress from one beam position to the next, this method of switching is not in general desirable for switching from any of the various output positions to a particular specified reset position such as "0." This occurs primarily since the tube operates within a magnetic field which causes the beam to step in only one direction. Therefore, the beam may "see" a change in spade potential only for three or four positions in the 25 direction it would normally advance under the influence of the magnetic beam. If a reset is attempted to a position nine positions removed from the existing beam position in a ten position tube, although it would only require switching to an adjacent compartment in a direction 30 contrary to the normal rotation of the beam, the change in potential of one spade would not cause the beam position to change. Accordingly, it is desirable to produce a reliable means and method for causing the beam to step from any of its various positions to a selected reset position 35 such as a "0" position in a decade counter tube.

A general object of the invention is to provide improved electronic reset circuits for beam switching tubes of the type described hereinbefore.

An object of the present invention is to provide a 40 system including a multiple position electron beam tube in which the electron beam may be caused to step reliably from any of its various positions to a reset position in response to pulses applied to a single input terminal.

Another object of the invention is to provide a magnetron type electron beam switching tube system in which both clearing and reset may be accomplished by a single 45 input signal.

In accordance with the invention, therefore, the beam is first cleared and then reformed, upon a particular spade. This is done in a single operation by providing circuit embodiments which operate in response to a single signal produced by a manual reset switch, or equivalent electronic switching device responsive to electronic pulses, to both reduce the potential momentarily 50 on all the spades simultaneously, and to delay the return of the selected reset spade to normal potential until after the remaining spade electrodes have returned to normal potential so that the beam will be reformed upon that particular beam position designated by the selected spade. 55 In this manner, the beam may be switched from any of its resident positions to the reset position because of the clearing operation immediately preceding the reset. The manner of resetting the beam as described in connection with the hereinafter proposed specific embodiments of the invention effects reliable reformation of 60 the beam in a time period compatible with the normal switching of the beam from one position to the next so that a reset of the beam from any of its various positions to the reset position may not substantially slow 65 down counting or switching operations performed by the tube.

Other objects and features of the invention will be

more fully understood from the following detailed description thereof when read in conjunction with the drawings, in which:

Fig. 1 is a perspective assembly view, partly in section, of a multi-position magnetron beam switching tube utilized with the invention;

Fig. 2 is a schematic diagram of a combined clearing and "0" set circuit embodiment incorporating the invention;

Figs. 3 and 4 are partial schematic diagrams indicating modifications of the invention; and

Figs. 5 and 6 are schematic diagrams of high speed electronic reset switches operable with the invention.

Referring now to Fig. 1, there is shown a perspective view of a magnetron beam switching tube which is used in accordance with this invention. This type tube is well known in the art, as evidenced by descriptions in publications such as Electronic Design for January 1954. Consequently only a brief description will be given herein of the structure and theory of operation of the tube 9 of Fig. 1. The cathode 41 is positioned within the hermetically sealed envelope 10. A plurality of elongated spade electrodes 31 through 40, having a U-shaped cross section, are positioned concentrically about the cathode 41 in spaced apart relation to one another. In the structure shown in Fig. 1, there are ten such spade electrodes.

Similarly, there are ten elongated target electrodes 11 through 20, having an L-shaped cross section, surrounding the spade electrode in a circular row centered on the cathode 41, and each associated with one of the ten spade electrodes. Each target with its two adjacent spades defines a compartment for receiving the beam in one of its ten stable locked in positions. Ten switching electrodes 21 through 30 are also positioned concentrically around the cathode 41 and are each individually positioned in one of the compartments between the open end of a target electrode and one extending leg of a spade electrode. For example, switching electrode 21 is positioned between the extending leg of spade electrode 40 and the open end of target electrode 11. The concentric magnet 42 placed about the envelope 10 produces a magnetic field in the tube that is substantially parallel to the elongated cathode 41. This magnetic field is of a polarity which will cause an electron beam extending outwardly from the cathode 41 to sweep around the tube in a clockwise direction (viewed from the top of the tube) in accordance with well known principles. Each of the spade electrodes is adapted to lock the electron beam in a particular compartment by a lowering of its potential. The beam remains locked in by means of the electron beam flowing through a spade impedance connected to the particular spade electrode upon which the electron beam is impinging thereby causing enough potential drop across said impedance to establish a substantially equipotential path somewhere between the two adjacent spade electrodes and the cathode, thereby causing the beam to impinge upon the interposed target electrode. The switching electrodes perform the function of causing the electron beam to impinge upon the next consecutive spade electrode by distorting the electric field within a particular compartment to cause the electron beam to advance to that spade electrode which will hold the beam in the compartment adjacent to the one upon which it impinges in the absence of a switching potential. It is to be noted that when the electron beam is directed to a compartment that the electron beam is actually impinging upon both the spade electrode and the target electrode. The target electrodes normally receive most of the electron beam since only a small portion thereof is required to lock the electron beam upon a particular spade electrode.

The tube of Fig. 1 is a particular preferred embodiment of a magnetic type beam switching tube which may be used in accordance with the invention, and other types of

switching tubes may likewise be used without distinguishing from the spirit or scope of the invention. In order to afford a comparison of the schematic circuits of following figures with the heretofore described tube construction, like reference characters will be used throughout the remaining figures of the drawing. In addition, the various elements of the tube are presented hereinafter in a different manner in order to make the functional operation of the drawing more easily understood. Thus, the electrodes of Fig. 2 are arranged in a straight line, and connections are made diagrammatically from the schematic switching circuit 50 to the corresponding sets of even and odd grid electrodes of the tube which are shown respectively as open and filled circles.

In the embodiment of Fig. 2, the coupling circuit 50, shown in left portion of Fig. 2, is utilized for stepping the beam from one target position to the next, and is connected in the conventional manner described in the above mentioned copending application to provide alternate switching signals to the corresponding groups of even and odd grid electrodes. Thus, should terminals 51 and 52 be coupled to corresponding output terminals of a binary counter or flip-flop circuit, they would serve to reduce the voltage of the corresponding grid circuits from their normal +30 volts to substantially cathode potential and thereby move the beam to an adjacent compartment. In each compartment there is a group of three electrodes, such as in the "0" compartment, the target 20, switching electrode 30 and spade 40. Thus, as the electron beam impinges upon the target 20 it produces an output signal at the "0" target terminal and causes enough beam current to flow upon spade 40 to cause a potential drop in flowing through the spade resistors 53, 54 and 55 to retain the spade 40 at a lower potential than spades 39 through 31. This occurs because spades 31 through 39, which include individual resistors 56 of substantially the same value as the combined resistance of resistors 53, 54 and 55, are not passing beam current. However, as the beam is stepped to a new position, say upon target electrode 19, the beam current will flow through resistor 56' and thereby reduce the potential upon spade 39 and cause the beam to be locked into position on target 19.

If it is assumed that the beam is impinging upon target electrode 19, the next input switching pulse would be at the odd switching input electrode 51 which causes the beam to fan out upon spade 38 and therefore advance to target electrode 18. Thus, the normal direction of advance of the beam is along the tube from compartments "0" through "9" successively and automatically back to "0" because of the coaxial arrangement of the tube electrodes as shown in Fig. 1. If desired, the spade resistor 56" coupled with the "9" position spade 31 may be made smaller in value so that the beam will not be stable and will clear or collapse automatically upon reaching a "9" count. In this event the beam may be reformed in the "0" compartment by an input potential at spade electrode 40 as applied to the terminal 58 located between resistors 53 and 54. This input potential could be taken directly from a target electrode of a preceding tube to provide a decade counter arrangement.

Should it be necessary to reset the tube manually, however, the switch contact 60 is provided. Obviously this may be any equivalent switch device such as an electronic tube or gating circuit which couples the clearing and zero setting lead 61 to ground or cathode potential. By closing the switch 60, current is caused to flow from the 150 volts spade potential terminal E_s through a resistor 64 commonly connected with all the spades 31 through 40 at the bus 65. This current flow caused by grounding lead 61 will result in reduction of the spade potentials to such an extent that the beam is dislodged from the locked in target position. In this respect the beam is at least partially extinguished so that it may be reformed upon the "0" spade electrode 40. The reduced spade po-

tential is momentarily applied by holding down the switch 60 manually or by a corresponding electronic pulse upon terminal 61 of sufficient duration to clear the tube by extinguishing the beam from its locked in target position.

As the switch 60 is released thereby ungrounding lead 61, the spades 31 through 39 almost immediately return to the +150 volt spade potential of terminal Es, since no beam current is flowing at this time through resistor 64. However, capacitor 68 is connected to shunt resistor 55 coupled between zero set lead 61 and the common bus 65 to cause the spade 40 to remain at reduced potential after the spades 31 through 39 are returned to their normal spade potentials. Accordingly, the necessary equipotential path is established to reform the beam to the target 20. Thus, the capacitor 68 is chosen to maintain the lowered potential upon spade 40 long enough for the beam to reform in the locked in position on target 20.

A bypass capacitor 69 may be provided in shunt with resistor 64 if necessary to reduce any tendency for degeneration action of resistor 64 during the clear and reset switching period. This degeneration is desirable in normal tube operation because changes of spade potential will thereby have less effect on tube operation as described and claimed in the copending application of J. Forman, Serial No. 574,478, filed March 28, 1956, and assigned to the same assignee as the present application. However, the tendency to degenerate during the switching and reset period would tend to impede the clearing and resetting function. Thus, consider the effect of resistor 64 as beam current begins to flow to the reset spade electrode 40 after switch 60 is opened. Beam current will cause the spade supply potential to be reduced which will thereby tend to reduce the potential of all the spades simultaneously and thereby tend to prevent reformation of the beam. However, capacitor 69 will serve to bypass the initial surge of beam current and thus eliminate the tendency for degeneration and permit the beam to be more reliably formed upon target 20. The time constant R55 C68 should exceed that of R64 C69 for proper operation.

Although it is obvious that various parameters may be used in connection with the invention, a range of typical values is shown in the following chart for the purpose of enabling those skilled in the art to better understand the nature of the invention and to find suitable parameters for employing it in other specific circuit environments, or with tubes having different characteristics than the described tube, which is a standard MO10-6700 type tube formerly supplied by Haydu Brothers of New Jersey, now the Electronic Tube Division of Burroughs Corporation. The corresponding values of the various accompanying components are as follows:

R56"	K ohms	33
R56 and 56'	do	100
R65	do	100
C69	mmf	290
R55	K ohms	2.2
C68	mmf	1000
R54	K ohms	82
R53	do	22
R70	do	4.7
R71, R72	do	100

In operation, therefore, it is evident that the structure of Fig. 2 serves to simultaneously reduce the potential upon all of the spade electrodes to clear the beam, while a momentary clear signal is utilized to ground lead 61 to cathode potential. The reformation of the beam on target 20 in the "0" compartment is performed also with the clearing signal by action of capacitor 68 in delaying the return of spade 40 to the normal spade potential of 150 volts until after the beam is formed in compartment "0" thereby causing the beam to lock in by beam current flow through the series resistors 53, 54 and 55.

Other embodiments of the invention may be constructed to operate in a similar manner such as, for example, the embodiment of Fig. 3. As seen from this embodiment the cathode 41 of the beam switching tube need not be grounded, and the common resistor necessary to reduce the spade to cathode potential upon the closing of switch 60 may be incorporated in the cathode to ground path of the tube. It is obvious in operation of this device to have the voltage divider action of resistors 55 and 64' as switch 60 is closed serve to reduce the spade to cathode potential in the same manner as the voltage divider action of Fig. 2 and thereby extinguish the beam. Likewise, the time constant provided by the shunt resistor 55 and capacitor 68 will serve to retain spade 40 in its lowered potential condition long enough to permit the beam to be reformed in the "0" compartment.

A still further embodiment of the invention is evident from consideration of Fig. 4 wherein the beam may be extinguished by opening the cathode circuit with reset switch 60'. The relay 90 is coupled in the common beam current path and returned to the +150 volt operating potential terminal 91 so that it opens its single set of contacts 92 when beam current flows. The contact 92 is normally closed to retain the spade 40 at ground or cathode potential. Thus, by opening switch 60' the beam is extinguished, thereby de-energizing relay 90 to lower spade potential 40. Thereafter as the contact 60' is reclosed the beam is reformed and upon the "0" compartment containing the lowered potential spade 40 to thereby re-establish beam current through relay 90 and open switch 92 for normal stepping operation of the tube.

The specific manner of employing electronic reset signals in the place of a manual switch 60 is shown in the embodiments of Figs. 5 and 6. Thus, Fig. 5 illustrates a direct current coupled high speed triode circuit operable with pulse widths of about one microsecond. The circuit may be used to replace the switch 60 hereinbefore described in connection with Fig. 2.

Likewise the blocking oscillator type of circuit shown in Fig. 6 may be used for alternating current coupling to the lead line 61 of the reset circuit in Fig. 2. This circuit assures that the clearing and reset operation is accomplished in a minimum time period approaching one microsecond even though the input pulse is shorter or longer than the switching pulse. Thus, if ΔT is the width of the input pulse and T is the spacing between two consecutive pulses, the circuit will reliably operate to reset under the conditions $1\mu\text{s} \leq \Delta T < 8T$, which signifies that the input pulse width ΔT may be anywhere between the limits of one tenth microsecond and eight tenths of the spacing between two consecutive pulses. The circuit values of the circuits of Figs. 5 and 6 are shown on the drawing and the turns ratio of the transformer in Fig. 6.

It is obvious from these embodiments that applicant has produced an improved manner of resetting the beam. Accordingly, those novel features believed to define the nature and scope of his invention are presented in the accompanying claims.

What is claimed is:

1. The method of resetting a multi-position magnetron beam switching tube having encompassed within its magnetic field a plurality of target and corresponding beam forming spade electrodes to a selected position comprising the steps of operating all the spade electrodes at a substantially identical positive potential, reducing the potential of one spade to form a beam on the corresponding target, simultaneously lowering the potential of all the spade electrodes enough to cause the beam to be cut-off and thereby removed from the target upon which it resides, restoring said positive potential to all the spade electrodes, and delaying the return of the potential of the spade of said selected position to said positive potential beyond the return of the remaining spade electrodes, whereby the beam is reformed to said selected position.

2. A circuit comprising in combination, a magnetron beam position tube having a cathode and a plurality of target and corresponding beam forming spade electrodes, a circuit for applying a potential to all of said spades positive with respect to said cathode, means for selectively switching the beam from target to target, individual resistors in said circuit for each spade of such value that the beam is locked in position as it impinges upon each target in response to beam current flowing to the corresponding spade, clearing means for momentarily lowering the potential to all of the spades simultaneously, and reset means cooperatively operative with the clearing means to delay the return of one designated spade to said positive potential with respect to the remaining spades upon termination of the lowering of potential by the clearing means.

3. In combination, a magnetron beam position tube having a cathode and a plurality of target electrodes each with a corresponding beam forming spade electrode, a positive spade potential source having a negative terminal connected with said cathode, individual resistances connecting each spade to the positive terminal of said source and having a value sufficient to hold the beam in a stable locked in position upon a corresponding target of any spade, a common resistor coupled in the spade beam current path, selectively operable momentary switching means connected between said cathode and the resistance of one spade electrode, whereby operation of the switching means serves to reduce the potential of all spades by current flow through said common resistor in sufficient magnitude to at least partially extinguish the beam and thereby to dislodge the beam from a locked-in position, and a capacitor coupled to the individual re-

5 sistance of said one spade electrode to delay the return of potential of said one spade electrode to said positive spade potential, whereby the beam is reformed upon said one spade electrode and the corresponding target electrode.

10 4. A combination as defined in claim 3 wherein the common resistor is connected in series between the tube cathode and said negative spade potential source terminal.

15 5. A combination as defined in claim 3 wherein the common resistor is connected in series between the tube spades and said positive spade potential source.

6. In a system employing a magnetron beam switching tube with a cathode and a plurality of target and corresponding beam forming spade electrodes, a combination clear and reset circuit comprising means for operating all of said spade electrodes at a normal positive potential, means for reducing the potential of one spade in response to beam current, clearing means for momentarily reducing the spade to cathode potential, and reset means for retaining the last mentioned reduced potential on a selected spade electrode for a longer time period than on the remaining spade electrodes.
